PADDLE FOR OPERATING IN THE FORE-
HEARTHS OF GLASS FURNACESFrederick William Armytage, Knottingley,
EnglandApplication November 26, 1937, Serial No. 176,744
In Great Britain December 2, 1936

2 Claims. (Cl. 49—14)

This invention relates to paddles for agitating or causing a flow of molten metal in the fore-hearts of glass furnaces, the chief object being to provide a new or improved paddle motion which can be varied to suit requirements.

According to the invention, the paddle has a compound continuously variable motion derived from two adjustable crank or eccentric mechanisms one of which controls the length of stroke of the paddle and the other of which controls the depth of entry of the paddle into the molten metal at each stroke. Thus, the arrangement may be such that the paddle motion may be varied from a circular movement to an elliptical movement with the major axis in either a more or less horizontal or vertical plane, the ratio of the major and minor axes being variable according to the relative adjustments of the controlling crank or eccentric mechanisms.

In order that the invention may be clearly understood and readily carried into effect, the same will now be more fully described with reference to and by the aid of the embodiment illustrated in the accompanying drawings, wherein:

Figures 1, 2, 3 and 4 are respectively a side elevation, rear elevation, plan, and a front elevation of the paddle gear, and Figure 5 is a fragmentary plan of the paddle and its mounting.

Referring to the drawings, the paddle blade 1 is carried from the forward end of a parallel link system 2 which is pivotally connected centrally at its opposite or forward and rear ends to the opposite ends of a supporting beam or lever 3. The parallel link system or link parallelogram comprises normally horizontal links interconnected at their forward and rear ends respectively by short links which are normally vertical, as shown, and which are pivotally mounted on the beam 3 by means of front and rear rock shafts 4, 5, respectively, so that the link parallelogram can be operated about these points of pivotal connection or mounting upon the beam or lever 3 to vary the angularity or deviation from the vertical of the forward and rear short links. In this connection the forward rock shaft 4 is revolutely mounted in the forward end bearings of the beam or lever 3 and is secured by a pin 6 to the forward short link of the parallelogram system 2 so as to partake of the angular motion imparted to said short link, and said rock shaft 4 extends laterally and carries upon its extended end the paddle blade 1 which is secured thereto by means of a depending rod or sleeve 7 and a coupling 8, whilst the rear short link which is pivoted upon or by means of the rock shaft 5, is

formed with or has fixed thereto an operating arm 9 which is pivotally attached to the upper end of a connecting rod 10 having its lower end pivotally connected to a nut 11 working on a screw 12, which screw 12 is adapted to be oscillated about a fixed centre or pivot 13 by a connecting link 14 and crank 14^x from the driving shaft 15 of the worm and worm wheel gear 16. The pivot 13 is on a bearing which rotatably receives a reduced unthreaded portion of the screw 12, and a similar bearing on the opposite end of the screw has the upper end of link 14 pivoted thereto. Thus as the screw 12 is oscillated a corresponding to and fro oscillation or stroke is imparted to the paddle 1 through the action of the parallel link system 2, and the length or amplitude of the stroke can be varied by adjusting the position of the nut 11 along the screw 12 by means of a hand wheel 12^x, whereby the screw 12 can be rotated. The fixed pivot 13 is carried by a stationary rear bracket 17 on a bed plate 18.

In order to provide for variation or adjustment of the depth of entry of the paddle 1 into the molten glass at each stroke, the supporting lever or beam 3 has its rear end or pivotal point 5 connected by a normally vertical link or radius arm 19 to the rear fixed bracket 17 and the centre point 20 of said lever or beam 3 is connected by normally horizontal and forwardly extending radius arms 21 to a forward fixed bracket 22, whilst the centre of the beam 3 is also connected through a connecting rod 23 and nut 24 to an oscillating screw 25 which is mounted on the pivot 13 and continuously operated by a separate crank 26 and connecting link 27. Thus an up-and-down motion is imparted to the outer end of the parallel link system 2 and the associated paddle 1 in addition to the stroke action, and said up-and-down motion can be controlled or regulated by adjustment of the nut 24 upon the screw 25 so that the depth to which the paddle 1 enters the glass can be varied. Screw 25 is pivoted on the rear bracket in the same manner as screw 12 and is connected with its associated link 27 in the same manner as screw 12 with link 14.

The connecting rods 10 and 23 are adjustable in length by means of coupling nuts 10^x and 23^x respectively working on the oppositely threaded ends of the two parts comprising each of said rods, the arrangement being such that the position of the parallel link system with its paddle can be adjusted either horizontally or vertically or both without altering the stroke action.

The beam 3 and associated gear is counterbalanced by a weight 28 connected by a cable 29

passing over a pulley 30 to the connecting rod 23 at its lower end.

The compound motion derived from the two crank actions or mechanisms may be varied from 5 a circular or approximately circular movement to an elliptical movement, the axes of which can be varied both in ratio and angular setting by appropriate adjustment of the screw gear associated with the crank mechanism.

10 I claim:

1. Apparatus of the class described comprising a beam, parallel shafts journaled in the ends of the beam, arms fixed to said shafts respectively, a link connecting said arms, a paddle fixed to one 15 of said shafts, means for rocking the other of

said shafts whereby said one of said shafts is likewise rocked through said link and said paddle is oscillated, and means for reciprocating at least that portion of the beam which supports said one of said shafts trans-axially of the latter so that 5 the paddle is caused to travel in an orbital path during oscillation.

2. Apparatus according to claim 1 wherein the beam is guided in its reciprocating movements by a link whose longitudinal direction is generally that of the common axial plane of said shafts and which extends transversely of said shafts. 10

FREDERICK WILLIAM ARMYTAGE. 15
